AEROPLANE CONSTRUCTION

Application filed January 19, 1931. Serial No. 509,580.

This invention relates to improvements in aeroplane construction and refers more particularly to an all metal plane construction including both the wings and fuselage assemblies.

This application is a continuation in part of a previous application filed by me, Serial No. 486,635, dated October 6, 1930.

The novelty in the wing assembly lies primarily in the overlapping of a plurality of corrugated sheets of varying thickness, the corrugations extending transversely of the line of flight. The thinner sheets overlap the sheets of thicker metal. Also, the sheets of varying thickness are of varying lengths so that the thinnest sheet extends from the base of the wing to the tips of the wing while the underlying sheets of greater thickness extend only so far toward the extremities of the wing as will produce adequate strength and rigidity to the construction as a whole.

The novelty in the fuselage construction lies principally in the forming of the ribs by crimping or corrugating one leg of angle bars and attaching to the smooth surfaces of the angles a stress sheet having corrugations extending in the line of flight and covering the stress skin or sheet by a plane surface covering.

Referring to the drawings; in Fig. 1 is shown a top view of one half of a wing made according to the present invention.

Fig. 2 is a sectional view taken along the line 2—2 in Fig. 1.

Fig. 3 is a section taken along the line 3—3 in Fig. 2, looking in the direction of the arrows.

Fig. 4 is a view taken along the line 4—4 in Fig. 3, looking in the direction of the arrows.

Fig. 5 is a detail of one of the ribs before it has been crimped.

Fig. 6 is a perspective view of a portion of the fuselage with parts broken away to disclose the sustaining ribs or bulkheads.

Fig. 7 is a sectional view taken through the fuselage at one of the ribs.

Fig. 8 is a detail showing the method of forming the ribs for the fuselage.

Referring to the drawings, the wing as shown in Figs. 1 to 4 inclusive, consists of a plurality of corrugated stress sheets designated as 1, 2, 3, and 4, covered by a plane surface sheet 5. The stress sheets are corrugated transversely to the line of flight as shown in Figs. 1 and 4. These corrugated stress sheets numbered from 1 to 4 inclusive are of varying thicknesses or gauges of metal, the sheet 1 being the lightest gauge or thinnest sheet and the underlying stress sheets 2, 3 and 4 increasing in thickness so that the sheet designated as 4 is of the heaviest gauge of metal. It will be noted that the stress sheet 1 extends from the base of the wing to the extremities of the wing. The stress sheet 2 extends from the base of the wing to a point somewhat short of the extremities of the wing. The stress sheet 3 extends from the base of the wing to a point about midway the length of the wing or is somewhat shorter in length than the stress sheet 2. The stress sheet 4 extends to about one fourth the length of the wing and is somewhat shorter than the stress sheet 3.

Instead of using a plurality of overlapping stress sheets, the invention contemplates the use of a single corrugated stress sheet varying in thickness from the base of the wing to the tips of the wing. Also the corrugations may be straight corrugations from the base to the outer extremities of the wing or the corrugations may be made tapered so that a large corrugation at the base of the wing tapers to a relatively small and narrow corrugation near the extremities of the wing.

The ribs which define the contour of the wing are preferably formed of angles 6 such as that shown in Fig. 5. One leg of the angle is crimped as shown in the sectional view in Fig. 3 at 6A. This crimping or corrugating of one leg of the angle or rib permits forming the rib in the desired shape to define the proper wing contour. Suitable struts, verticals or diagonals, are positioned to give the rib the desired strength and rigidity. Along the trailing edge of the wing is a false spar 8 which is attached both to the ribs and to the trailing edges of the stress skin by means of 100

formed angle members 9. To the false spar is pivoted at 10 the ailerons 11.

To assemble the wing, the stress sheets are first overlapped and riveted and the smooth surface covering positioned outside of the corrugated stress sheets and riveted. The ribs are then placed at their proper interval and the lower flanges of the ribs riveted to the stress sheets and outer covering sheet. 5 The stress sheets and covering sheet are then brought around the leading ends of the ribs and riveted in place to the upper flanges of the ribs from front to rear. Finally, the false spar is placed in the trailing edge of the wing and riveted or otherwise fastened to the angles 9, which are in turn fastened to the ribs. The trailing edge of the wing beyond the false spar is finished off by riveting there-to flat sheets reinforced by channels. By this 10 type of construction, there is eliminated the necessity of using a spar which considerably decreases the weight of the wing, and the necessary strength is procured by the overlapping of the corrugated sheets of varying 15 thickness. The false spar in the trailing edge of the wing takes the horizontal shear to which the wing is subjected.

Wing construction of this type may be used either in a full cantilever monoplane wing 20 of either rectangular or tapered form, or is adaptable for use in externally braced monoplane or biplane wings. Where externally braced, the axial loads imposed by struts or wires are taken directly into the monocoque 25 or shell type construction through the reinforced ribs.

This wing construction varies from the disclosure in my previous application in that the stress sheet in the previous application was 30 made up of a plurality of short lengths terminating at each rib. By the present construction, the stress sheets extend over a plurality of ribs. By this type of construction, the necessity of riveting each section 35 at the joints or ribs is eliminated and only sufficient riveting is required to hold the ribs in position and transfer strain from the stress sheets to the ribs. This reduction in riveting 40 greatly decreases the weight.

To form the fuselage an angle 12 similar to that used for forming the ribs is crimped as shown in Fig. 8. The depth of the corrugations determines the diameter of the bulkheads as used in the fuselage shown in Fig. 45 6. Over the outer surface of these circular bulkheads are placed the corrugated stress sheets 13 which are fastened preferably by riveting to the smooth surface leg of the 50 angles which form the bulkheads.

Outside of the corrugated stress sheets is a plane surface covering or skin 14. The details of attaching this covering to the stress sheet and the stress sheet to the circular ribs is 55 more completely disclosed in my previous ap-

plication, Serial No. 486,635, dated October 6, 1930.

In the drawings there are but three overlapping stress sheets shown, but it is contemplated that any number of sheets may be 70 used according to the length of the wing spread and the necessary strength required. In a cantilever wing constructed for a monoplane of the low wing type, eight overlapping, corrugated stress sheets were used of 75 the following thicknesses:

The first sheet extending to the wing tip gauged .010"

The second underlying sheet gauged .010"

80

The third sheet gauged .010"

The fourth sheet gauged .010"

The fifth sheet gauged .016"

The sixth sheet gauged .020"

The seventh sheet gauged .020"

The eighth sheet gauged .032"

85

From this it will be noted that sheets of increasing thickness were used, overlapped so that the thinner sheets extended substantially to the wing tip, while some of the shorter sheets which did not extend to the tip of 90 the wing were of the same gauge and the sheets of thicker gauge constituted the shorter sheets adjacent the base of the wing where the greatest stresses are encountered. No claim is made to the particular thicknesses but 95 to the use of variable thicknesses and extending these sheets of variable thickness for different lengths toward the wing tip in order to procure the desired strength.

In the drawings, it will be noted that the 100 tip of the wing is squared off parallel to the line of flight. The wing tips are finished off by a rounded tip as are the ends of the tail group, including the elevators and the vertical rudder.

105

I claim as my invention:

1. An all metal wing construction comprising a stress sheet made up of a plurality of overlapping corrugated sheets of varying thickness or gauges of metal, the thinnest sheet extending from the base to the tips of the wing and the remaining sheets of varying thickness extending only so far as to give adequate strength and rigidity to the wing structure.

110

2. An all metal wing construction comprising a stress sheet made up of a plurality of overlapping sheets corrugated transversely to the line of flight, a plane covering skin enveloping the corrugated sheets, and ribs 120 positioned at intervals to define the contour of the wing, the corrugated sheets being of varying thicknesses or gauges of metal, the thinnest sheet extending from the base to the tips of the wing and the underlying corrugated sheets of increasing thickness extending only so far toward the tips of the wing as to give adequate strength and rigidity to the wing structure.

125

3. An all metal wing construction com-

130

prising a stress sheet made up of a plurality of overlapping sheets corrugated transversely to the line of flight, a plane covering skin enveloping the corrugated sheets, and ribs positioned at intervals to define the contour of the wing, the corrugated sheets being of varying thicknesses or gauges of metal, the thinnest sheet extending from the base to the tips of the wing and the underlying corrugated sheets of increasing thickness extending only so far toward the tips of the wing as to give adequate strength and rigidity to the wing structure, and a false spar attached to the trailing edges of the upper and lower stress sheets.

15 4. Fuselage construction for aeroplanes comprising a plurality of substantial circular rib members formed by crimping or corrugating one leg of angle bars, a corrugated stress sheet attached to the smooth side of the angles having the corrugations extending in the line of flight, and a smooth surface covering sheet enveloping the corrugated stress sheet.

20 5. Fuselage construction for aeroplanes comprising a plurality of substantial circular rib members formed by crimping or corrugating one leg of angle bars, a corrugated stress sheet attached to the smooth side of the angles having the corrugations extending in the line 25 of flight.

30 In testimony whereof I affix my signature.
